UNITED STATES PATENT OFFICE.

GEORGE W. GREENE, OF LOUISVILLE, KENTUCKY, ASSIGNOR TO TEN BROECK TYRE COMPANY, OF LOUISVILLE, KENTUCKY, A CORPORATION OF DELAWARE.

DESIGN FOR A TIRE.

46,670.

Specification for Design.

Patented Nov. 24, 1914.

Application filed August 20, 1914. Serial No. 857,780. Term of patent 7 years.

To all whom it may concern:

Be it known that I, GEORGE W. GREENE, a citizen of the United States, residing at Louisville, in the county of Jefferson and State of Kentucky, have invented a new, original, and ornamental Design for Tires, of which the following is a specification, reference being had to accompanying drawing forming part thereof, in which—

Figure 1 is a plan view of the tire forming the subject of my new, original and ornamental design, and Fig. 2, is a cross sectional view, on the line 2—2, Fig. 1.

The design for tire forming the subject of my invention, comprises a rounded tread portion 10, a circumferential rib 11; which rib is staggered and raised from the surface of such tread; transverse arms 12 joining said circumferential rib 11 and terminating

in rounded knobs 13, with rounded knobs 14 interspersed between said arms 12; the knobs 14 on the respective sides of the central circumferential rib 11 being disposed opposite said arms 12. The raised portions disposed on the surface of the tire tread have walls that are beveled or inclined with respect to said surface.

I claim:

The ornamental design for a tire, as shown and described.

In testimony whereof, I have signed my name to this specification, in the presence of two subscribing witnesses.

GEORGE W. GREENE.

Witnesses:

E. W. WILSON,
C. J. FRANZ.
